(57) **CLAIM**

The ornamental design for a plant support structure, as shown and described.

DESCRIPTION

FIG. 1 is an angled perspective view of a plant support structure in an assembled condition;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof;

FIG. 8 is a front view thereof in a disassembled condition; and,

FIG. 9 is a front perspective view of the plant support structure of FIG. 1, shown with environment.

The broken line showing is included for the purpose of illustrating environmental structure and forms no part of the claimed design.

1 Claim, 8 Drawing Sheets
